UNITED STATES PATENT OFFICE.

OMAR ELMER CLARK, OF DENVER, COLORADO, ASSIGNOR TO THE DENVER ROCK DRILL MANUFACTURING COMPANY, OF DENVER, COLORADO, A CORPORATION OF DELAWARE.

MOTOR FOR METERS.

1,203,488.

Specification of Letters Patent.

Patented Oct. 31, 1916.

Application filed December 19, 1913. Serial No. 807,695.

To all whom it may concern:

Be it known that I, OMAR E. CLARK, a citizen of the United States, residing at Denver, in the county of Denver and State 5 of Colorado, have invented new and useful Improvements in Motors for Meters, of which the following is a specification.

The present invention relates to motors for meters, and in the embodiment disclosed, is particularly intended and adapted for that class of meters employed for measuring expandible fluids, such as air under pressure.

The primary object is to provide a structure of the piston type, which will operate accurately in order to measure and register the amount of air or the like passing through the same, irrespective of the speed or volume, and so constructed that it requires but 15 little energy to effect the operation of the parts and the actuation of the registering mechanism.

A further and important object is to produce a simple structure of this character 20 made up of comparatively few and inexpensive parts, so that it may be manufactured at comparatively small cost, and is not likely to become deranged.

One embodiment of the invention is illustrated in the accompanying drawings, wherein:—

Figure 1 is a longitudinal sectional view in a horizontal plane of the meter. Fig. 2 is a detail sectional view through a portion 25 of the piston, showing the rifle bar and nut. Fig. 3 is an end elevation of one of the cylinder heads. Fig. 4 is a vertical sectional view therethrough. Fig. 5 is a horizontal section. Fig. 6 is an end elevation of one 30 of the valves. Fig. 7 is a detail sectional view through a portion of one of the valves, showing the mounting therefor.

Similar reference numerals designate corresponding parts in all the figures of the 35 drawings.

In the embodiment disclosed, a cylinder member is employed, comprising a cylindrical body 8, to the ends of which are fastened heads 9 and 9^a by means of screws 50 or other devices 10. These heads have axial bores, which are in turn closed by caps 11 and 11^a secured thereto by screws 12. A reciprocating piston 13 operates in the piston chamber 14 of the cylinder member, 55 and comprises a central web 15, having op-

positely extending flanges 16, which have overhanging and outwardly projecting ribs 17, thereby forming chambers 18 on opposite sides of the central web 15.

In one of the heads, as 9^a, is formed an intake port 19 surrounded by an internally threaded nipple 20 to permit the attachment of a supply pipe. In the other head is formed a corresponding outlet or exhaust port 21. From the intake port 19, a passageway 22 leads to an annular groove 23 formed in the head, and another passageway 24, leading from said port 19 through the body 8 of the cylinder member, is in communication with a corresponding annular groove 25 formed in the opposite head 9. Another groove 26 is formed in the head 9^a outside the groove 23, and is in communication with the outlet or exhaust port 21 through a passageway 27 extending therefrom and longitudinally through the body 8 of the cylinder member, as will be clear by reference to Fig. 1, this passageway being partly formed by an annular groove 28 formed in the head 9 outside the groove 25. 70

Fitted into the bores of the two heads 9 and 9^a, are outwardly tapered bushings 29 having cylindrical bores 30 forming valve seats or bearings, and these bushings have openings, respectively designated 31, 32, 33 85 and 34 that afford communication between the grooves 26, 23, 25 and 28 and the interiors of said bushings. Slidably mounted in the bushings, are valves 35, which, as clearly shown in Fig. 6, comprise hubs 36 90 provided with radial spokes 37 that in turn, carry rims 38, which fit the bores of the bushings. Each of the rims 38 is sufficiently wide to cover one set of the ports through the bushings 29, as will be obvious, and the valves are movable to alternately cover and uncover the ports of each set. These valves are connected by a rod or stem 39 that passes through the hubs 36 of the valves, and through bushings 40 inserted in said hubs. 100

The bushings 40 are located on the ends of the rod or stem 39, which are reduced, as shown at 41, and said bushings are provided at their inner ends with annular flanges 42, constituting stops for the valves. Washers 105 43, abutted against the outer sides of the valve hubs, prevent the detachment of the valves from the bushings, and these washers are in turn held in place by cap nuts 44 threaded on the ends of the rod or stem 39. 110

With this structure, the valves are permitted to float loosely on the connection, the distance between the flange 42 and the washer 43 being slightly greater than the length of the hub of the valve, and the diameter of the hole through the hub is slightly greater also than the diameter of the bushing engaged therein. The function of this loose fit is to take care of any misalignment of the several parts, which might affect the easy movement of the valve. The cap nuts 44 also serve the double purpose of holding or clamping together the parts, and furthermore constitute a positive and accurate stop, their outer ends abutting against hardened pads in the form of headed plugs 45 that are inserted in the caps 11 and 11^a in the paths of movement of said cap nuts.

It will also be noted by reference to Fig. 1 that the inner ends of the valve casing bushings 29 project beyond the inner ends of the heads 9 and 9^a, and that said ends of the heads are provided with annular ribs or flanges 46 spaced from the projecting ends of said bushings, thereby forming annular grooves 47 in the inner ends of the hubs, which grooves receive the projecting bosses or ribs 17 on the opposite ends of the piston. As a result, pockets are formed that receive said ribs 17, and the ribs inasmuch as they trap air therein, form with the pockets or grooves, dash pots which cushion the piston without jar or vibration at the ends of its stroke.

The piston 13 is freely slideable upon the rod or stem 39, being provided with a packing bushing 48 surrounding said rod or stem. There are also placed on the said rod or stem 39, coiled springs 49 that are located on opposite sides of the piston and bear against the flanges 42, being alternately borne against by the piston during its reciprocation. These springs constitute the means for actuating the valves, and are compressed, as will be evident, by the piston. The valves are, however, normally locked against movement while the springs are being compressed, and for this purpose, latches 50 are pivoted, as shown at 51 in the heads 39 of the cylinder member and engage the washers 43. Actuating plunger rods 51^a, slidably mounted in bearings 52 carried by the bushings 29, are pivoted, as shown at 53 to the latches, and springs 54, coiled about the pivots 51 and 53 and bearing against the caps 11 and 11^a, serve to urge the latches into their operative positions.

Suitably mounted on one of the caps, as 11, is a register or counting mechanism, 63 designated 55, which may be of any well known or desired construction, having an actuating shaft 56 that is journaled in a bushing 57 placed in the cap 11, and is keyed, as shown at 58 to the trunnion 59 of a rifle bar 60 journaled at one end by means

of said trunnion in the bushing 57 and journaled at its other end in a bushing or thimble 60^a in the opposite cap 11^a. A rifle nut 61 in the piston is engaged with the rifle bar, and is held in place and against movement with respect to the piston by a suitable set screw 62.

Briefly described, the operation of the apparatus is as follows: Air or other fluid is supplied to the motor from any suitable source, through the intake 19, and will thus find access to the grooves 23 and 25 by means of the passageways 22 and 24. The valves, being in the position shown in Fig. 1, the fluid will enter through the ports 31 into the piston chamber 14, at the left side of the piston, and thus drive said piston to the right, the fluid in advance of said piston, passing through the right hand valve 35, and through the ports 34 and the groove 28 to the outlet or exhaust 21, by means of which it will be delivered from the meter. As the piston moves to the right, the spring 49 in advance of the same, will be compressed or placed under tension, but the valves 35 cannot move, inasmuch as they are locked by the latch 50 at the right hand end of the machine. As the piston continues to advance, however, it will strike the projecting end of the plunger rod 51^a, forcing it longitudinally against the action of the spring 54, and causing the latch 50 to become disengaged from the latch mechanism. When thus disengaged, the spring 49 will act to force both valves simultaneously to the right, thereby covering the ports 34 and 31 and opening the ports 33 and 32. When this movement takes place, and fluid will flow through the passageway 24 and groove 25 into the right hand end of the piston chamber 14, thereby forcing the piston to the left, while the fluid in advance of said piston, will now pass through the port 32, the groove 26, the passageway 27, and out through the port 21 from the machine. As the piston advances, the left hand spring 49 will be compressed, but the valves will not move under the action of the spring until the piston strikes the left hand plunger rod 51^a and releases the opposite latch. The piston therefore, will be moved back and forth and during its reciprocatory movement it will oscillate the rifle bar 60 one-tenth of a revolution on each stroke. This turning movement will be imparted to the shaft 56 of the register, and therefore on each double stroke of the motor, the said register will be operated one increment.

From the foregoing, it is thought that the construction, operation and many advantages of the herein described invention will be apparent to those skilled in the art, without further description, and it will be understood that various changes in the size, shape, proportion, and minor details of con-

struction, may be resorted to without departing from the spirit or sacrificing any of the advantages of the invention.

Having thus fully described my invention, what I claim as new, and desire to secure by Letters Patent, is:—

1. In a structure of the character set forth, the combination with a cylinder member and a piston operating therein, of a valve, a spring bearing against the valve and borne against by the piston during its movement, and a latch normally holding the valve against movement and operated by the piston.

15 2. In a structure of the character set forth, the combination with a cylinder member having intake and outlet ports in both ends thereof, of a piston operating in the cylinder member between the ports, a valve for each set of ports movable longitudinally of the cylinder member, a longitudinally movable rod directly connecting the valves and fixed thereto, and means actuated by the piston for controlling the movement of 25 both valves.

3. In a structure of the character set forth, the combination with a cylinder member having intake and outlet ports in both ends thereof, of a piston operating in the cylinder member between the ports, tubular valve seats for the ports disposed longitudinally of the cylinder member, longitudinally movable valves within the seats, shiftable alternately over the ports, a rod directly connecting the valves, and means actuated by the piston for controlling the movement of both valves.

4. In a structure of the character set forth, the combination with a cylinder member having intake and outlet ports in both ends thereof, of a piston operating in the cylinder member between the ports, tubular valve seats for the ports disposed longitudinally of the cylinder member, a rod directly connecting the valves, said piston being slideable upon the rod, springs on the rod interposed between the piston and the valves, latches for holding the valves against movement, and actuating plungers for the 50 latches extending through the valves and located in the path of the piston.

5. In a structure of the character set forth, the combination with a cylinder member having a tubular valve seat and lateral inlet and outlet ports opening thereinto, of a valve operating in the seat and comprising a hub and a rim with spaced spokes connecting the same, said rim being shiftable between the ports, a valve stem mounted in the hub, a piston operating in the cylinder member, and means actuated by the piston for operating the valve.

6. In a structure of the character set

forth, the combination with a cylinder member comprising a body and a head therefor, 65 said head having a longitudinally disposed tubular valve seat, and lateral inlet and outlet ports opening thereinto, a valve operating in the seat and comprising a hub and a rim with spaced spokes connecting the 70 same, said rim being shiftable between the ports, a valve stem mounted in the hub, a piston operating in the cylinder member, and slideable upon the valve stem, and means actuated by the piston for operating the 75 valve.

7. In a structure of the character set forth, the combination with a cylinder member having a head with inlet and outlet passageways, of a detachable bushing in the 80 head having lateral ports communicating with the passageways, a valve slideable longitudinally in the bushing and having a rim movable laterally to positions across the lateral ports, a valve stem carried by the valve 85 and extending longitudinally into the cylinder member, said valve having a passageway therethrough for permitting fluid to pass between the cylinder member and one of the ports, a piston in the cylinder member 90 slideable upon the valve stem, a spring interposed between the piston and the valve, a latch for holding the valve against movement, and an actuating device for the latch located in the path of the piston.

8. In a structure of the character set forth, the combination with a cylinder member comprising a body and detachable heads for the body, said heads having inlet and 100 outlet passageways, of detachable tapered bushings located in the head longitudinally of the cylinder member and having lateral ports communicating with the passageways, a valve in each bushing slideable longitudinally of the cylinder member, each of said valves comprising a hub and a rim movable over the ports, and spokes connecting the hub and rim, a rod directly connecting the hubs and extending longitudinally through 110 the cylinder member, a piston slideable in the cylinder member upon the rod, springs interposed between the pistons and the heads, a latch coöperating with each valve 115 to hold it against movement, and a plunger for each latch located in the path of the piston and extending through the adjacent valve.

In testimony whereof I have hereunto set my hand in presence of two subscribing 120 witnesses.

OMAR ELMER CLARK.
